Inventor. L. H. Whitney.

United States Patent Office.

LEVI H. WHITNEY, OF VALLEJO, CALIFORNIA

Letters Patent No. 74,782, dated February 25, 1868.

IMPROVEMENT IN FIRE-LIGHTERS.

The Schedule referred to in these Letters Patent and making part of the same.

Be it known that I, LEVI H. WHITNEY, of Vallejo, county of Solano, in the State of California, have invented a new and improved Device or Mode of Constructing a Fire-Lighter; and I do hereby declare that the following is a full and exact description thereof, reference being had to the accompanying drawings, and to the letters of reference marked thereon.

The nature of my invention consists, first, in the mode of containing the oil and supplying it to the wick-socket; second, the wick-socket, which contains the wick, is screwed on the tube, containing the oil, and the combination of the tube and wick-socket forms a device or torch for igniting wood, charcoal, or other material for kindling fires in all kinds of stoves, fireplaces, or any place where it is necessary to kindle a fire; third, the wick, made of any compacted material suitable for wicks to burn coal or other oils, and forced into the wick-socket tight and close; fourth, the packing inside the tube to retard the too great flow of oil to the wick-socket.

To enable others skilled in the art to make and use my invention, I will proceed to describe its construction.

Figure 1 is a perspective view.

Figure 2 are the tube and wick-socket in operation.

Figure 3 shows another mode of constructing the wick-socket.

Figures 4 and 5 represent modifications in the form of nozzle or wick-tube.

To construct the fire-lighter, take common brass or iron tubing of any desirable diameter and length, the most convenient and suitable-sized tubing being three-fourths ($\frac{3}{4}$) of an inch inside and seven-eighths ($\frac{7}{8}$) of an inch outside diameter, and eighteen (18) inches long. Cut screw-threads on one end and close the opposite end. The wick-socket may be cast, of brass or iron, with inside diameter somewhat smaller than that of the tube, and with a taper, and tap the larger end and screw on the tube, inserting a gasket of soft metal, rubber, or leather to make a close joint. The wick is made of cotton-rope or other and cheaper material suitable for the purpose, and two to four (2 to 4) inches long, and wound with thread to compress and make it solid. The packing A in tube may be made of thick felt-cloth, cut in suitable size to fit the chamber of tube, and secured together with a wire to facilitate adjusting and removing it to fill the tube with oil.

Its use: Fill the tube with coal-oil, light the wick, place it under the grate of a coal-stove, or in the fire-box of a wood-stove, and place over the blaze some small wood, and immediately it becomes ignited, when the fire-lighter is removed and extinguished.

What I claim as my invention, and desire to secure by Letters Patent, is—

An article of manufacture, a fire-lighter, constructed of the parts arranged substantially as described.

LEVI H. WHITNEY.
